UNITED STATES PATENT OFFICE.

CHARLES T. SCHOEN, OF MEDIA, PENNSYLVANIA.

SPOOL FOR MUSIC-ROLLS.

1,143,143.

Specification of Letters Patent. Patented June 15, 1915.

Application filed November 14, 1914. Serial No. 872,186.

To all whom it may concern:

Be it known that I, CHARLES T. SCHOEN, a citizen of the United States, residing at Media, in the county of Delaware and State 5 of Pennsylvania, have invented a certain new and useful Improvement in Spools for Music-Rolls, of which the following is a full, clear, and exact description.

The object of this invention is to provide 10 a music roll spool, for use in player-pianos and other musical instruments; which spool is also capable of use in other instruments or apparatus where an article rolled or wound on the spool is utilized by unrolling 15 or unwinding it therefrom.

The invention consists of a spool of the character and for the uses above referred to, having a metallic barrel, preferably cylindrical, and more or less resilient, to one end 20 of which is fitted a metallic head capable of movement in the direction of the length of the barrel to compensate for atmospheric or hygroscopic conditions influencing the roll on the spool, and another head fixedly applied to the other end of the spool and serving as a medium by or through which power 25 may be applied to turn the spool, the other head turning with the barrel also, as I will proceed now to explain and finally claim.

In the accompanying drawings illustrating 30 the invention, in the several figures of which like parts are similarly designated, Figure 1 is a perspective view, the barrel being cut in two about midway of its length 35 to show its construction. Fig. 2 is a longitudinal section, the barrel being broken away between ends. Fig. 3 is a perspective view of a barrel detached illustrating features shown in Fig. 1 and also showing the 40 meeting edges of the barrel in close touch instead of sensibly separated as in Fig. 1. Fig. 4 is a plan view of the blank from which either head may be made, and Figs. 5, 6 and 7 are cross-sections showing successive steps in the process of converting the 45 blank of Fig. 4 into heads such as shown in Figs. 1 and 2.

The barrel or tube 1 is made most economically by flanging a sheet of metal, preferably steel, this flange being engaged by a mandrel and the sheet then rolled into tubular form,—a common and well-known process, whereby adjacent edges are brought 50 opposite one another and a tube formed 55 which has an open side formed by such juxtaposed edges. The flange 2 is located in-

side of the tube and serves to stiffen it. As shown in Fig. 1, a slot 3 may be left between the flanged edge and the opposite edge, or, as shown in Fig. 3, these edges may be 60 brought into such close touch as to close the tube substantially. One end of the tube is provided with opposite longitudinal slots 4 to admit of the movement of one of the heads in the direction of the length of the 65 tube. The head referred to is designated 5, and comprises a hub 6 having a hole 7 in its outer end, and a laterally extending flange 8 at its other end. The flange 8 has its rim 9 curled over to reinforce it as well as to 70 afford a slightly and smooth finish. This head is secured to the barrel or tube 1 in any suitable way or by any suitable means 75 that will admit of it moving in the direction of the length of the barrel in order to compensate for movement of the contents of the spool due to atmospheric or hygroscopic conditions or influences. As shown, the slotted end of the tube enters the hub, and the yielding connection consists of prick points 80 or indentations 10 entering the slots 4; and while these connections permit movement of the head independently of the barrel, they also serve to cause the head to turn with the barrel. The other head 11 likewise has a 85 hub 12, with a slot 13 in its outer end to engage a turning medium, and a laterally extending flange 14 at its other end provided with the curled edge 15. This head is fixed to the other end of the barrel or tube 1 by 90 entering such end in the hub thereof and then using any suitable means to rigidly connect them, such as simultaneously formed interlocking indentations 16 in the hub and barrel. 95

The heads may be pressed from sheet steel, and in so forming them, a discous blank 17, Fig. 4, is first cupped, as shown in Fig. 5, with a rim flange 18, and then this cupped and flanged blank is pressed to the 100 shape shown in Fig. 6, where the hub 19 is definitely formed, and then the flange 20 has its rim 21 pressed up as shown in Fig. 7, to be subsequently curled over as shown in Figs. 1 and 2, as previously described. 105

A barrel divided longitudinally by the slot 3, or by having its edges meeting more or less closely, that is to say, an open-sided barrel, is preferable to a solid barrel, in that no fitting has to be done in applying 110 the heads, but, on the contrary, the open-sided barrel is more or less springy and so

may have the heads applied to it very readily. As a consequence, the spool may be produced very economically. Using metal throughout results in a spool that is 5 very durable and not injuriously subjected to the atmospheric changes, such as occur in wooden spools. The movable fit of head 5 allows for the expansion of the roll or contents when damp, and permits the use 10 of a continuous single piece barrel, light in weight and very stiff and strong and perfectly straight at all times.

As already sufficiently indicated, the invention contemplates variations in structural details.

What I claim is:—

1. A spool for music rolls, comprising a continuous single piece resilient barrel, and heads applied to opposite ends thereof to 20 turn with it, and means to permit movement of one of the heads on the barrel in the direction of the length of the barrel, the resiliency of the barrel admitting of the ready application of the heads thereto without 25 additional fitting.
2. A spool for music rolls, comprising a sheet metal barrel having one side open from end to end, a hubbed head fixed to one end of the barrel, and a hubbed head mov- 30 ably connected with the other end of said barrel, the barrel yielding transversely to engage the hubs and thereby compensating for any variation in diameter between the hubs and barrel.
3. A spool for music rolls, comprising a sheet metal barrel having one side open from end to end, a hubbed head fixed to one end of the barrel, said barrel having longi- 35 tudinal slots in its opposite end, and a hubbed head applied to the slotted end of the barrel and engaging the slots therein, the barrel yielding transversely to engage

the hubs and thereby compensating for any variation in diameter between the hubs and barrel.

4. A spool for music rolls, comprising a sheet metal barrel of tubular form, pro- 45 vided with an interior stiffening flange ex- tending throughout its length, having one side open so as to render the barrel more or less springy, and one end slotted, a hubbed head having one end of the barrel extending within its hub and the two rigidly connected by interlocking the hub and barrel, and a second and similar hubbed head having the 50 other end of the barrel connected therewith in a manner permitting the movement of the head in the direction of the length of the barrel, and compelling rotation there- 55 with, the springiness of the barrel compen- 60 sating for any inequalities in the fit of the hubbed heads on the barrel.

5. A spool for music rolls, comprising a sheet metal barrel of tubular form, pro- 65 vided with an interior stiffening flange ex- tending throughout its length, having one side open so as to render the barrel more or less springy, and one end slotted, a pressed steel fixed head having a hub interlocked with the barrel, and a similar pressed steel 70 head having a hub engaged with the barrel to turn with it and to move thereon in the direction of its length, the springiness of the barrel admitting of the ready application 75 of the heads thereto without additional fitting.

In testimony whereof I have hereunto set my hand this 13th day of November A. D. 1914.

CHARLES T. SCHOEN.
